CONTAINER

Huna L. Apfelbaum, Brooklyn, N. Y., assignor to
 Victor Metal Products Corporation, Brooklyn,
 N. Y., a corporation of New York

Application March 6, 1942, Serial No. 433,612

2 Claims. (Cl. 206—42)

This invention relates to pill boxes and particularly to those from which one pill at a time may be removed by the user.

The containers or boxes heretofore made to dispense a single pill at a time have baffles or covers or the like associated therewith which conceal the contents so that the user cannot know when the box is empty except by shaking it and rattling the contained pills. Such boxes cannot be depended on to operate with perfect efficiency at all times to discharge a pill even when they have pills therein. Nor can the boxes heretofore devised be easily molded of plastic material.

The present invention therefore contemplates the provision of a simple, easily molded container having a removable cover and a series of slotted tubes or tubular members each adapted to hold a stack of pills, whereby the uppermost pill in each stack is exposed for removal when the cover is removed while the remaining pills are adequately protected.

The invention further contemplates the provision of a comparatively inexpensive protective container for pills which may be molded of a small amount of plastic material, occupying little space for the number of pills which it can hold, which may hold a number of different types of assorted pills and from which the selected exposed pill of a stack may be quickly and easily removed with the fingers without the necessity of touching or moving other pills in the container.

The various objects of the invention will be clear from the description which follows and from the drawing, in which,

Fig. 1 is a front view of the container with the cover partly broken away to show the interior.

Fig. 2 is a top plan view of the same.

Fig. 3 is a top plan view of the container portion with the cover removed and showing one stack of pills.

Fig. 4 is a front view of the same with one of the tubes partly broken away.

Fig. 5 is a vertical section of the same taken on the line 5—5 of Fig. 4.

Fig. 6 is a similar section taken on the line 6—6 of Fig. 4.

Fig. 7 is a side view of Fig. 4.

In the practical embodiment of the invention shown by way of example, the container is made of two pieces and consists of the cover part 10 and the container part 11. Each of these parts is preferably molded in one piece of suitable plastic material such as synthetic resin of any well-known type. The cover has a preferably flat top

13 and a wall 14 depending from the periphery of the top and forming the front, back and rounded ends of the box when in place on the container part.

5 The container part 11 comprises the base 15 provided with the outstanding ledge 16 against which the lower edge of the cover wall 14 is adapted to abut and rest (Fig. 1) with the outer surface 17 of the cover flush or coplanar with the outer or lateral surface of the base, said base being of substantially the same size and shape as the top 13 of the cover. Upstanding integrally from the base are the preferably spaced hollow cylinders or tubes 18, 19, 20, 21 each of a diameter slightly less than the width of the base. The tubes may be arranged in a single row as shown, or in a number of rows or in staggered relation as may be found convenient. A stack as 22 of pills may be inserted into each of the tubes through the open top thereof, there being illustrated three pills in each stack.

It will be understood that by making the tubes of a different predetermined height than that shown, more or less pills will be received in each tube. It will also be seen that each tube may receive pills of types different from those in the other tubes if desired, and the tubes may be correspondingly labelled to avoid confusion and to permit selection of the desired pill. The uppermost surface and part of the lateral surface of the uppermost pills of the stack are exposed for withdrawal of the selected uppermost pill when the cover 10 is removed from the box. To permit the withdrawal of the top pill or the two or more top pills from any stack, each tube is provided 25 with a pair of diametrically opposite vertical slots as 24, 25 each of sufficient width to permit parts of the thumb and finger of the user to pass therethrough into engagement with the pill or pills to be withdrawn (Fig. 3). Said slots may terminate at their lower ends slightly above the ledge 16 or sufficiently above the bottom of the lowermost pill of the stack to enable the fingers to engage the lowermost pill after the others have been 30 withdrawn. The unslotted lower part of the tube cooperates with the cover to prevent the entrance of dust or other foreign matter into the box. To permit the fingers to grasp the pill to be removed easily, the side walls 32, 33 of the slot may converge inwardly to provide a longer dimension at the outside of the tube than at the inside.

The tubes 18, 19, 20 and 21 are arranged closely adjacent each other, the adjacent sections of the walls thereof merging into a single wall at 35 and adjacent to the line joining the axes of the

tubes. Where the walls join, they may be thickened slightly as at 26, 27, to form flat upright parallel surfaces between the tubes terminating at one end at the top of the container part and at the lower end terminating at the reinforcing, sealing and cover guiding walls 30, 31. Each of the outer surfaces 34, 35 of said walls 30 and 31 is preferably tangent to a set of the outermost corresponding edges of the slots 24, 25 and extends on the front or back of the container part between the slots of the end tubes of the row of tubes. The top 33 of the walls 30, 31 is slightly above the bottom of the slots 24, 25 but sufficiently below the top of the container part to minimize the amount of material used therein.

To provide a proper guiding, frictional and sealing contact between the inner surface of the front and back parts of the cover wall 14 and the upright surfaces 34, 35, the distance between said surfaces is equal or substantially equal to the distance between the inner front and rear surfaces of the cover wall 14. The end parts of said cover wall fit snugly on to the outer surfaces of the end tubes 18, 21 of the row.

Even if some of the pills have been removed from the stack, the remaining pills can move only through a limited distance, that is, the remaining heights of the tubes, and consequently are not so likely to become damaged or pulverized when the box is handled, as when the pills are held in an ordinary box and can then move freely about in the comparatively large space left vacant on the removal of a substantial number of pills.

It will be seen that there has been provided a box which may be molded easily, which adequately protects the pills against contamination due to handling and exposure and from which a single or any desired number of pills may be selected when desired without disturbing or handling the others, and that there has been produced hereby a device well designed for the purposes intended.

Modifications of the invention within the spirit thereof are intended to be included in the scope of the appended claims.

I claim:

1. A two-piece molded box comprising a molded one-piece container part and a molded one-piece cover, the container part comprising a base, a row of hollow cylindrical portions each open at the top and upstanding from the base, each of said cylindrical portions being adapted to receive and hold a stack of pills and having a pair of upright diametrically opposite slots therein extending from the open top to a point in upward spaced relation to the base, each of said slots

having inwardly converging edges adapted to receive therebetween the fleshy part of the finger of the user to remove the top pill of a selected stack, each of the cylindrical portions having an outer diameter less than the width of the base to provide an outstanding ledge on the upper surface of the base, each of said cylindrical portions being of uniform thickness except at the juncture thereof with an adjacent one of said portions to provide a series of spaced recesses between the slots, each of the recesses having a pair of convex walls joined at their inner edges by a flat upright wall, flat upright front and rear walls on the container part each extending upwardly from the upper surface of the base and each being tangent to corresponding outer edges of the slots and terminating along a line in upward spaced relation to the bottoms of the slots and at the bottoms of the aforementioned recesses, the cover having a top terminating in semi-circular ends, and a wall depending from the periphery of the top, the bottom edge of said depending wall resting on the ledge, the end parts of the inner surface of said wall engaging the convex outer surfaces of the end cylindrical portions of the row, the remaining inner surface of said wall engaging the front and rear upright walls of the container part and extending downwardly past said slots in the operative position of the cover on the container part.

2. A box comprising a one-piece molded container part having a base and a plurality of vertically slotted hollow cylindrical portions of substantially uniform thickness upstanding from the base, the adjacent portions being integrally joined at the adjacent sections of the respective walls thereof, the lower sections of said portions being integrally joined to each other and to the base by an upright wall having flat front and rear surfaces substantially tangent to the cylindrical portions and having end surfaces substantially coincident with the convex outer surfaces of the end cylindrical portions, there being recesses in the container part between the adjacent cylindrical portions and above the front and rear surfaces of said wall, the recesses being substantially V-shaped in cross-section, the slots of said cylindrical portions being extended downwardly into said wall and terminating at points in upward spaced relation to the base, and a hollow molded cover having a depending wall engaging the outer surfaces of the end cylindrical portions of the row and also engaging the front and rear surfaces of said upright wall when the cover is in place on the container part.

HUNA L. APFELBAUM.
